UNITED STATES PATENT OFFICE.

LEWIS H. BURNHAM, OF HAVERHILL, MASSACHUSETTS, ASSIGNOR OF ONE-HALF TO
GEORGE E. CLARK, OF HAVERHILL, MASSACHUSETTS.

SHOE-UPPER HOLDER.

1,323,009.

Specification of Letters Patent. Patented Nov. 25, 1919.

Application filed February 26, 1919. Serial No. 279,440.

To all whom it may concern:

Be it known that I, LEWIS H. BURNHAM, a citizen of the United States, and a resident of Haverhill, county of Essex, State 5 of Massachusetts, have invented an Improvement in Shoe-Upper Holders, of which the following is a specification.

This invention relates to certain improvements in that class of devices which are employed in shoe factories for the purpose of holding a considerable number of shoe uppers, after they have been assembled and before they are placed on the last, so that they may be readily carried from one point to 15 another in the factory.

More specifically, the invention relates to that class of devices which are known as "upper horses" and comprises a form of yoke, usually of wire, onto one or more of 20 the arms of which the upper pieces are passed, fastening means being provided which engage the free end of the upper holding arm to hold the uppers in place thereon.

25 These devices have been found to be objectionable in practical use in that the fastening means thereof is liable to become disconnected or detached, and, in consequence, lost or misplaced.

30 In case the fastening means become detached from the upper holding arm, the uppers are likely to fall off, and, in consequence, much inconvenience is likely to be caused, and, in case the fastening means is 35 lost, the rest of the device becomes useless until another can be supplied.

The objects of my invention are to provide a device of the above character which is provided with a form of fastening means 40 which will not be disconnected by accident or become separated from the rest of the device, and which is adapted to be made entirely of strong wire, so that it will be durable and may be made at a reasonably 45 small cost.

I accomplish these objects by the means shown in the accompanying drawing in which:—

Figure 1 is a side elevation of the complete device.

Fig. 2 is a plan view thereof and

Fig. 3 is a perspective view of the arm-fastening means.

According to my invention, I provide a 55 frame or yoke of stiff wire bent into suit-

able form, said wire being somewhat resilient, but adapted to be bent into various shapes and to retain such shape under normal conditions. Said yoke comprises two parallel side-members or arms *a* and *b* connected at their lower ends by a bottom portion *c*, which is continuous therewith, said bottom portion being preferably provided with an intermediate coil or loop *d* to increase the resilience thereof. These parts, 60 normally, all lie in the same plane. At the upper or free end of the member *a* the wire is bent at right angles and extended in the said plane of said members for a portion of the normal distance between said members, 65 as indicated at *e*, then is bent to form a complete eye *f* at its end, then is bent to extend upwardly at right angles and then transversely to the plane of the frame to form a hook *g*. 70

A link *h* is provided which is composed of a short length of the same material and is bent to form an eye *i* in one end, which is interlocked with the eye *f*, the wire of which the eye *f* is formed being passed through 80 the eye *i* before said eye *f* is completed, so that the link is permanently connected, and is free to swing in all directions. The opposite end of the link *h* is provided with an oblong-shaped, longitudinally-disposed loop 85 *k*, so formed that it is normally held in a plane at right angles to the plane of the yoke. The end portion of the arm *b* is bent to form a head or eye *m* in a position at right angles to the plane of the yoke, the 90 diameter of said head *m* being substantially greater than the width of the slot of the eye *k* and substantially less than the length thereof, and its thickness being less than the width of said slot, so that the head *m* 95 may be passed through the eye *k* when held longitudinally thereof, but cannot pass therethrough in a position transverse thereto, as shown in the dotted and full line positions, respectively, of Figs. 2 and 3. 100

It is to be noted, in this connection, that the head *m* is, in effect, oblong in form as its width is substantially greater than its thickness.

As previously stated, the material of which 105 the frame is constructed is resilient, so that the arms of the yoke may be swung relatively.

To connect or disconnect the link *h* with the arm *b*, the free end portion of said arm 110

is pushed to one side of the plane of the frame to the extent of the length of the link, and, at the same time, toward the other arm, to a point about midway of the frame, 5 as indicated in the dotted line position of Fig. 2. This movement may be readily accomplished by holding the device by the hook *g* with one hand and by pressing the arm *b* into said position with the other. 10 When the link is on the arm *b*, as in Fig. 1, it will be swung into a position at right angles to the plane of the frame, in which position the loop *h* of the link may be easily placed on, or removed from the end of the 15 arm *b*, as indicated by the dotted line position of Fig. 2, after which the arm will be permitted to spring back to its normal position.

While the link *h* is disconnected from the 20 arm, the uppers may be readily placed thereon, and, to reconnect it, the arm *a* is swung back to the distorted position at one side of the normal plane of the yoke, and the link is replaced in position on the arm described.

25 As the frame must be considerably distorted to permit the disconnection of the link from the arm, and as there are practically only two positions (one at each side of the plane of the frame) in which disconnection is possible, it is apparent that disconnection thereof by accident is practically impossible, so that all danger that the uppers will be removed by accident is avoided. On the other hand, connection and disconnection 30 of the link can be quickly made when desired.

As the device is constructed entirely of wire, bent into the desired form, it may be manufactured at a practically minimum expense. 40

I claim:—

1. A shoe-upper holder comprising a frame having a resiliently supported upper receiving arm provided with an oblong head at 45 its free end, a link pivoted at one end to said frame and having an oblong aperture in its free end adapted to receive said head when the longer dimensions thereof are in approximate coincidence and to receive the end portion of said arm adjacent said head in all the relative positions thereof, the relative disposition of said head and said aperture being such that the longer dimensions thereof are in transverse relation in the 50 normal position of the arm and are in coincident relation in a distorted position thereof.

2. A shoe upper holder comprising a yoke having a resilient upper-receiving arm provided with an oblong head, at its free end, disposed transversely of the normal plane of the yoke, a link pivotally connected to the opposite portion of the yoke and having a longitudinally disposed, oblong eye, in its 55 free end portion, constructed and arranged

to be passed over said head in a distorted position of said arm and to be held on said arm with its eye in transverse relation to said head to prevent its removal, in the normal position of said arm. 70

3. A shoe-upper-holder comprising a yoke having resiliently connected arms, a link pivotally connected to one of said arms and having an oblong shaped eye at its free end, a head of oblong form on the end of the other of said arms, the relative size and arrangement thereof being adapted to permit the eye of said link to be passed over said head when the arm thereof is sprung out of its normal position and to be held transversely of said eye when permitted to resume its normal position, to prevent disconnection of the link. 75 80

4. A shoe-upper holder comprising a resilient yoke having the arms thereof normally disposed in approximate parallelism, an oblong-shaped head at the free end of one of said arms so arranged that its longer dimension extends approximately perpendicularly to the plane of said arms, a link 90 pivoted at one end to the other of said arms and having an oblong eye in its free end arranged with its longer dimension extending longitudinally thereof, in position to receive the end portion of said first named arm adjacent the head thereof, and adapted to be passed over said head when the arm thereof is distorted to bring the longer dimensions of said head and said eye into approximate coincidence. 95 100

5. A shoe upper holder comprising a yoke of resilient wire formed to provide a pair of approximately parallel arms, the end portion of one of said arms being bent transversely to form an oblong-shaped head, a link pivotally interlocked with the other and formed at its free end to provide an oblong eye having its longer dimension extending longitudinally thereof and adapted and arranged to be passed over said head when the arm thereof is distorted to a position at one side of the normal plane of said arms and approximately midway between the normal positions of said arms to bring the longer dimensions of said head and eye into approximate coincidence and to be held in transverse relation thereto in the normal position of said arms, to lock the link in position thereon. 105 110 115

6. A shoe-upper holder comprising a frame having a holding arm resiliently retained in a normal position and adapted to be sprung aside to a distorted position against such resilient action, a link pivoted at one end on said frame and constructed for pivotal connection at the opposite end with the end portion of said arm, to permit movement of the arm from its normal to its said distorted position while pivotally engaged with said link, and means on the end 120 125 130

of said arm disposed in position to prevent disconnection of said link therewith when the arm is in normal position and to permit such disconnection when the arm is sprung aside to said distorted position.

7. A shoe-upper holder comprising a U-shaped frame of resilient material composed of a supporting arm, and an upper-receiving arm and an intermediate connecting portion all normally disposed approximately in the same plane and constructed to permit said receiving arm to be moved into a relatively distorted position at one side of such plane, a link pivotally connected to the upper end portion of said supporting arm and constructed for pivotal connection at the opposite end with the end portion of said receiving arm to permit movement of the latter to said distorted position while pivotally connected thereto, and means on said receiving arm preventing disconnection of said link therefrom when in the normal position thereof and permitting such disconnection of said link therefrom in the distorted position thereof.

8. A shoe-upper holder comprising a U-shaped frame of resilient material composed of a supporting arm, an upper-receiving arm and an intermediate connecting portion all normally disposed approximately in the same plane, and constructed to permit said receiving arm to be moved into a relatively distorted position at one side of such

plane, a link pivotally connected to the upper end portion of said supporting arm and having an aperture at its opposite end adapted to receive the end portion of said receiving arm, to provide a pivotal connection therewith and constructed to permit movement of the latter to said distorted position while disposed in said aperture, and a head on the end of said receiving arm, said head and said aperture being relatively formed to prevent disconnection of said link from said arm when in the normal position thereof and to permit such disconnection when in the distorted position thereof.

9. A shoe-upper holder comprising a frame having a resiliently supported upper receiving arm provided with a head of a form other than round at its free end, a link pivoted at one end to said frame having an aperture in its free end, shaped similarly to said head and adapted to receive the same when the corresponding dimensions thereof are in approximate coincidence and to receive the portion of said arm adjacent said head in the different relative positions thereof, the relative disposition of said head and of said aperture in said link being such that passage of said link onto and off said arm is prevented in the normal position thereof.

In testimony whereof I have signed my name to this specification.

LEWIS H. BURNHAM.
